ABSTRACT OF THE DISCLOSURE

A vortex-stabilized radiation source wherein one of the electrodes has a recess therein, the recess having a generally radial bottom wall which forms the arcing surface of the recessed electrode. Means are provided to drain gas from the peripheral region of the recess.

This invention relates to a light or radiation source of the type wherein the light emanates from a high-current electric arc. More particularly, the invention relates to a vortex-stabilized radiation source and method characterized by high efficiency and arc stability, long electrode life at high power levels, readily-controllable emission, and other important advantages.

It is becoming increasingly recognized by workers in the field of light (radiation) sources that the vortex-stabilized arc produces highly superior results. Stabilization by vertical gas flow compares very favorably to stabilization by axial gas flow, and to other forms of stabilization. In order to provide a satisfactory radiation source, a major portion of the vertically-flowing gas must discharge from the arc chamber through an outlet located adjacent the arc (electrical discharge) and also located at or near the axis of the chamber. Another requirement is that the light generated by the arc must be transmitted therefrom through at least a portion of the wall of the chamber, as distinguished from being transmitted through the gas-outlet opening. Relative to the latter factor, it has been found that the emission of light from the decaying plasma produced by electric arcs (not from the electric arcs themselves) is inefficient.

In discharging the vertically-flowing gas from the arc chamber, at a region adjacent the arc and also adjacent the axis of the chamber, it was for a number of years thought to be optimum to effect such gas discharge through a single outlet opening which is coaxial with the chamber axis. Such a radiation source produced major benefits when compared to the prior art. Thus, for example, the efficiency of transmission of light from each exposed section of the arc was markedly superior to the transmission efficiency relative to arcs stabilized by axially-flowing gas. On the other hand, it was found that a large portion of the arc itself extended into the axial discharge conduit, so that radiation from such arc portion in the conduit was largely obscured. This factor, in combination with factors such as the increased voltage required by the long arc (and because of the fact that the gas flowed rapidly adjacent the footpoint of the arc), rendered the over-all efficiency of such vortex-stabilized radiation source relatively low.

A further important characteristic of vortex-stabilized radiation sources, of the above-indicated type wherein the gas exhausts through a single axial outlet opening, is that two strong light-emission zones are in evidence—one adjacent the cathode and the other extending into the outlet opening in the anode (the outlet opening being normally provided in the anode). The presence of two such emission zones is very different from the usual short arc lamp, for example, because in such lamps the only strong emission zone is adjacent the cathode. The indicated strong or hot emission zone within the anode opening transmits

2

large amounts of heat energy to the anode, by conduction, radiation and electron collisions. Such large amounts of heat are detrimental to anode life, as well as being detrimental to radiative efficiency.

Although the above-indicated vortex-stabilized radiation sources, of the single axial-outlet type, have for years been regarded as optimum, they have recently been very substantially improved upon. Thus, in co-pending patent application Ser. No. 421,370, filed Dec. 28, 1964, for an Apparatus and Method for Generating Light, inventors John W. Winzeler and Delbert G. Van Ornum, a radiation source is described wherein the arc is relatively short and the voltage requirement greatly reduced so that a much improved efficiency results. Furthermore, such source is characterized by important advantages relative to emission characteristics, and relative to gas pressure-drop characteristics at varying power levels. However, such source is also subject to certain disadvantages, one of which is that efficient operation may not be sustained at very high power levels.

It is, therefore, a primary object of the present invention to provide an apparatus and method for generating light, which apparatus and method eliminate various disadvantages relating to the above-specified and other, radiation sources.

A further object is to provide an apparatus and method for generating light in a manner characterized by high efficiency, extremely long electrode life at high power levels, controllability of the emission characteristics of the arc, controllability of the shape of the arc, and other important advantages.

A further object is to provide a radiation-source apparatus and method characterized by a relatively small anode fall voltage, whereby a high current may be achieved at relatively low voltage so that the radiation efficiency increases markedly.

A further object is to provide a double-walled light source having improved gas-inlet means.

A further object is to provide a light-source apparatus and method wherein only a small portion of the gas flowing through the exhaust outlets is directly heated by the arc, thereby achieving advantages including long electrode life.

These and other objects will become apparent from the following detailed description taken in connection with the accompanying drawings in which:

FIGURE 1 is a view, primarily in longitudinal section, of a radiation source constructed in accordance with the present invention;

FIGURE 2 is a fragmentary transverse sectional view on line 2—2 of FIGURE 1;

FIGURE 3 is a section on line 3—3 of FIGURE 2;

FIGURE 4 is an enlarged view of the central portion of the showing of FIGURE 1;

FIGURE 5 is a transverse section on line 5—5 of FIGURE 4;

FIGURE 5a is a section on line 5a—5a of FIGURE 4;

FIGURE 6 is a fragmentary view, corresponding to the left portion of FIGURE 4 but showing a modified form of the invention;

FIGURE 7 is a sectional view along line 7—7 of FIGURE 4; and

FIGURE 8 is a fragmentary sectional view on line 8—8 of FIGURE 7.

Referring first to FIGURE 1, the illustrated apparatus comprises first and second metal body elements 10 and 11 comprising flanges 12 and 13 on stems 14 and 15, respectively. Extended between the flanges 12 and 13 is a relatively large-diameter tubular outer envelope 16 which may be formed of quartz, fused silica, or other suitable transparent material. Extended between the opposed inner

end portions of the stems 14 and 15, in coaxial relationship relative to outer envelope 16, is a tubular inner envelope 17 which may be formed of the same material. Envelopes 16 and 17 define between them an annular outer chamber 18 into which gas is introduced as will be indicated subsequently, such chamber being maintained sealed from the chamber defined within inner envelope 17 by suitable O-rings 19 or other seals. The chamber defined within envelope 17, between the opposed inner ends of stems 14 and 15, is the arc chamber and has been given the reference number 20.

Proceeding next to a preliminary description of the stem 14, the cylindrical main body of such stem (which is coaxial with both chambers 18 and 20) is provided with a central chamber or bore indicated at 22. The inner end of the stem, radially outwardly of bore 22, is shaped exteriorly as a frustoconical surface 23, such surface being one of the end surfaces of the anode element of the present construction. The frustoconical surface 23 is shown as merging with a radial surface 24 which lies in a plane perpendicular to the common axis of chambers 18 and 20. The remaining and highly important components of the anode (formed by the inner end of stem 14, and by associated parts) will be described hereinafter, after a description of the associated cathode, power means, gas-flow means and cooling means.

The stem 15, which normally forms the cathode of the apparatus, may be shaped with the illustrated conical inner end portion 26 which is coaxial with the common axis of chambers 18 and 20. The base of the conical exterior surface of end 26 merges with a radial surface 27 which is perpendicular to such common axis. The region radially-outwardly of the base of cone 26 receives relatively cool gas which is delivered thereto through passages or conduits 28, such passages being oriented (as will be described) to effect a strong vortical flow of gas in arc chamber 20 about the axis thereof. Gas enters the passages 28 from an annular groove 29 which is formed in stem 15 adjacent one end of envelope 17.

The gas-inlet passages 28 to arc chamber 20 are best shown in FIGURES 4, 7, and 8. Such passages extend in a direction toward the interior surface of inner envelope 17, so that the inflowing gas will cool and clean such envelope. Thus, the ends (inner) of passages 28 which directly communicate with chamber 20 are shown as being located adjacent the junction of surface 27 with the conical surface of element 26. The remaining (outer) ends of the passages, which communicate with annular groove 29, are disposed closer to the axis of the apparatus, so that the above-indicated direction of gas flow toward envelope 17 results.

As best shown in FIGURE 8, the passages 28 not only extend toward envelope 17 but, much more importantly, extend in a direction which is generally tangential to the axis of chamber 20, so that the necessary vortical or helical gas flow is achieved. Preferably, a substantial number of inlet passages 28 are provided, four such passages being illustrated in FIGURE 7. Passages 28 are identical to each other, and are spaced 90 degrees apart.

Each of the passages 28 is inclined at an acute angle (shown as 45 degrees, FIGURE 8) to a plane containing the axis of the light source, in such relationship that the gas flow in chamber 20 will be smoothly helical in nature. This produces benefits including increasing arc stability, and decreasing the gas pressure drop through chamber 20.

The gas which is delivered to the annular groove 29, and thus through passages 28 to arc chamber 20, is supplied to annulus 18 (FIGURE 1) through one or more inlet passages indicated at 31 in FIGURES 1-3. Passage 31 is oriented in such manner as to effect a helical flow of gas in the annulus 18 between envelopes 16 and 17, the gas spiraling longitudinally along envelope 18 and then entering the annular groove 29. Such spiral flow is highly beneficial in uniformly cooling all parts of both envelopes.

Gas is supplied to the inlet passage or passages 31 through a recirculation conduit 32 in which are interposed a suitable pump 33 and heat exchanger 34. The heat exchanger 34 effects cooling of gas which discharges from arc chamber 20 through the anode, by means of passages and conduits to be described hereinafter.

The cathode 26 is water cooled in a suitable manner. For example, as shown in FIGURES 1 and 4, the stem 15 may be formed with a longitudinal passage or opening 36 into which is inserted a water-inlet conduit 37. Water introduced through conduit 37 impinges against the apex portion of the cathode cone 26, and then flows outwardly (radially around conduit 37) for discharge through an outlet 38.

A suitable current source 39, preferably adapted to deliver a very high current, is connected between the elements 10 and 11 (which are formed of copper or other highly conductive material) by means of leads 41 and 42. A starter circuit, indicated schematically at 43, may be interposed in one of the leads (for example, number 42) in order to initiate the discharge between the electrodes. The starter circuit may include means to create a momentary high-voltage or high-frequency pulse discharge.

The current source 39 should be a D.C. source having the positive terminal thereof connected to element 10, so that the inner end of stem 14 serves as the anode as previously indicated. It is to be understood, however, that reverse polarity may be employed if desired. It is also to be understood that various other current sources, for example A.C. sources, pulse sources, etc., may be employed if desired.

DETAILED DESCRIPTION OF THE ANODE ASSEMBLY

Stated generally, the anode is provided with a recess or opening 45 which is coaxial with the arc chamber 20, the bottom of the recess (at least in the vicinity of the axis of arc chamber 20) being closed.

Stated more definitely, the recess 45 has an annular wall 47, shown as being cylindrical about the axis of arc chamber 20. The bottom of recess 45 is shown as comprising a wall 48 lying generally in a radial plane (generally perpendicular to the axis of the arc chamber). The central region of wall 48 may protrude somewhat in a direction toward the cathode. Recess 45 may be termed the "foot chamber or opening," because the arc seats or foots therein.

The diameter of the wall 47 should be substantially greater than the diameter of the arc 49 which is generated along the axis of chamber 20, it being understood that the arc diameter (in chamber 20) varies in accordance with power level, gas-flow conditions, gas pressure, etc. The diameter of wall 47 is another factor (as will be described relative to FIGURE 6) operating in a very substantial manner to determine the diameter of the major portion of arc 49, namely the arc portion which is fully exposed within chamber 20.

For maximum-efficiency operation, the diameter of the portion of annular wall 47 closest to cathode 26 should not be substantially smaller than the axial distance from wall 48 to surface 24. Such portion of wall 47 defines an opening through which recess 45 communicates with arc chamber 20.

To state the above in another manner, the bottom wall 48 of the recess 45 should, for highest-efficiency operation, be sufficiently close to the arc chamber 20, namely to the radial surface 24 in the illustrated configuration, that light emanating from the center of wall 48 (at the axis of the arc chamber) will be transmitted in a generally radial direction (as well as an axial direction) as indicated by the phantom lines 51 in FIGURE 4. The ratio of the diameter of recess 45 to the depth thereof may be termed the aspect ratio, and may be varied as 75 will be described hereinafter relative to FIGURE 6.

The gas-discharge passages 46 are shown as communicating with the recess 45 at the periphery of the arcing wall 48. Alternatively, or additionally, passages 46 may communicate with recess 45 at regions closer to radial surface 24 (spaced from wall 48). A plurality of such gas-discharge passages should be provided, in spaced relationship around the recess. Thus, in the illustrated form, three such passages or conduits 46 are shown. The three passages 46 have radially-extending nozzle portions 52-54 (FIGURE 5a) which intersect the wall 47 of the recess 45. Such nozzle portions 52-54 (forming the intake ends of passages 46) communicate with the main portions of passages 46, the latter extending in inclined manner through a cooling (heat transfer) section of the anode as will be described hereinafter.

In all cases, the distance between surface 24 and intake means 52-54 is short, and should be less than the diameter of the portion of wall 47 closest to the cathode 26.

The described provision of an arcing electrode portion 48 through which gas does not discharge, in combination with the peripherally-located gas discharge means 52-54, and further in combination with the annular element 47, provide major advantages relative to such factors as power capability, efficiency, emission characteristics, electrode life, etc. It is emphasized, however, that a substantial factor relative to the present light source and method relates to the manner of cooling the walls of recess 45 to provide a heat-sink action which combines with the pressure-sink action effected by passages 46.

Proceeding next to a description of the cooling means, and to a further description of the gas-discharge means, the stem 14 of the anode is provided with a solid, re-entrant portion 56 having a cylindrical peripheral wall 57 coaxial with the axis of the stem 14 and of the chamber 22 therein. The base of re-entrant portion 56, that is to say the inner end of the chamber 22, is located in spaced relationship from anode surfaces 23 and 24, generally radially-outwardly of the bottom wall 48 of recess 45. There are thus formed large cross-sections through which heat may be transferred from the walls of recess 45 to the inner end of chamber 22.

A metal tube 58 is connected to (or integral with, as shown) the end of re-entrant portion 56, and extends axially of chamber 22 for connection to the conduit 32 through which the gas recirculates. Each of the gas-outlet passages 46 communicates with the passage formed in tube 58.

A water-separator tube or conduit 59, having a diameter substantially larger than that of tube 58, extends into the chamber 22 into telescoped relationship with re-entrant portion 56. The inner diameter of the water separator tube is slightly larger than the diameter of wall 57, so that an annular gap 61 is provided as shown in FIGURE 4 (such gap being so small as to prevent illustration thereof in FIGURE 1).

The annulus 62 between tubes 58 and 59 communicates with a plurality of angularly-shaped coolant passages 63-65 having corner or elbow portions disposed adjacent the arcing bottom wall 48 of recess 45. Such passages 63-65 not only have inlet ends communicating with annulus 62 but also have outlet ends communicating with chamber 22 radially-outwardly of water-separator tube 59.

Water is introduced into the annulus 62 by means of an inlet conduit 66 (FIGURE 1), and flows to the right through such annulus (FIGURES 1 and 4) to effect a certain amount of cooling of the gas which passes outwardly through tube 58. Upon reaching the inner end of annulus 62, the water separates, one portion flowing through the annular gap 61 (FIGURE 4) and the other portion flowing through the elbow-shaped passages 63-65. The water then flows to the left, through the annulus which is defined radially-outwardly of water separator 59 and within the chamber 22, for discharge through an outlet conduit 67.

In the described manner, relatively cool water is delivered to the region surrounding the base of re-entrant

anode portion 56, and is also delivered directly (through passages 63-65, FIGURE 5) to the region adjacent the arcing wall 48 of the anode. This effects an extremely efficient cooling of all wall portions of recess 45. In addition, the walls of the gas-discharge passages 46 are effectively and efficiently cooled. In the latter connection it is pointed out that the number of gas-discharge passages 46 is preferably equal to the number of water passages 63-65, and that such passages are offset (as shown in FIGURE 5) so that one gas passage lies between each two adjacent water passages. The amount of heat transfer from the gas-discharge passages to the water is thus comparable to the heat transfer from the walls of recess 45 to the water.

15 DESCRIPTION OF THE METHOD, AND OF VARIOUS CRITICAL RELATIONSHIPS

Stated generally, the method of the invention comprises effecting gas vortex stabilization of a high-current electric arc in a chamber, causing at least one footpoint of the arc to extend into an opening in at least one of the electrode assemblies between which the arc is maintained, effecting footing of the arc in the opening, discharging gas from the opening through conduit means communicating therewith and having an intake portion located near the chamber, and transmitting light from such arc through a window in the wall of the chamber. The method further comprises cooling the wall portions of the opening or recess in order to provide a heat-sink action which cooperates with the pressure-sink action caused by the outlet-conduit means. Such heat-sink and pressure-sink actions augment the vortex stabilization effect, and facilitate footing of the arc.

30 Stated in another manner, the method of the invention comprises providing an arc chamber having a wall which is a surface of revolution about a central axis, maintaining a high-current electric arc along such axis between spaced electrodes, causing one end portion of such arc to extend into a recess which is defined by a wall coaxial with and spaced outwardly from such axis, footing the arc on the bottom wall of the recess, effecting generally tangential introduction of gas into a peripheral region of the arc chamber, preventing discharge of gas from the recess along such axis, discharging gas from the recess through passage means which communicate with the recess at least one region disposed radially-outwardly from the axis, and transmitting light from the arc through the surface of revolution.

35 It is pointed out that the gas discharges from arc chamber 20 (not recess 45) through an axial opening (namely, recess 45) in one of the electrodes (the anode). However, such axial opening is relatively large in diameter and, furthermore, is not a continuous straight conduit but instead has a bottom arcing wall 48 which prevents discharge of gas along the exact axis of the recess. Thus, the arc does not extend into the gas-discharge passages 46 but instead foots on the wall 48. Furthermore, and very importantly, the arc spreads after entering the recess 45 to provide a generally conical footing region 68 (FIGURE 4) which merges with the generally cylindrical main body of the arc 49. Such spreading of the arc over the majority of the area of arcing wall 48 reduces current density at the electrode, greatly increases electrode life, and changes the emission characteristics of the arc as will be indicated hereinafter.

40 The gas discharges from the chamber 20 at a region adjacent the arc and also relatively adjacent the axis of the arc chamber, as is required for efficient vortex action in a radiation source. However, the gas does not discharge from the recess 45 along the axis thereof but instead in the generally radially-outward direction through the portions 52-54 of the gas-discharge passages 46. Because of the fact that the arc does not extend into such passages, and because of the efficient water cooling of

such passages as described above, there is only a very small amount of erosion of the passage walls.

The annular wall 47 of the recess or opening, although relatively large in comparison with prior-art constructions of the type wherein the gas discharges through a long axial passage or conduit, has been found to produce a surprising degree of arc stabilization and constriction. As indicated above, the diameter of wall 47 is caused to be sufficiently large to permit efficient transmission of light from arcing surface 48, and sufficiently large that the electrode will not melt or erode excessively at surface 47, but sufficiently small to effect the desired degree of constriction and stabilization of the arc 49. Because the wall 47 is located radially-outwardly from a portion of the arc, the diameter of the wall 47 has a much greater bearing on the diameter of arc 49 than would be the case if the wall 47 were spaced axially from the arc. Thus, for example, the indicated arc 49 (within chamber 20) has a diameter substantially smaller than would be the case if a cylindrical arcing member were connected axially to surface 48 and extended out of recess 45 into chamber 20 (there then being no arc portion within the recess).

The intake ends 52-54 of passages 46 are sufficiently close to the arc to effect an efficient draining off of the layer of partially-excited gas between the arc 49 and the relatively cool, vertically-flowing gas surrounding the arc. As described in co-pending patent application such as the one cited above, such draining off of the partially-excited gas increases the efficiency of transmission of ultraviolet radiation from the hot core of the arc through the window or envelope 17.

Because there is no substantial axial gas-outlet opening in arcing wall 48, the gas present within the hot core of the arc 49 is relatively stagnant. Such gas being relatively stagnant, it may be maintained in an extremely hot, highly-excited condition with a minimum of energy. Stated in another manner, observation of the arc indicates that only a small portion of the gas moving through the exhaust holes 52-54 is directly arc heated, most of the exhaust gas coming instead from the partially-excited gas around the arc column 49. The result is a significant increase in the efficiency of the radiation source.

It is emphasized that, for a given pressure in the main body of arc chamber 20, the pressure at the axis of such chamber is substantially higher in the present source than in constructions wherein the gas discharge is through a straight passage along the axis. Stated otherwise, the gas pressure along the axis of chamber 20 is maintained relatively high because the gas is relatively stagnant at such axis, instead of being continuously drained. The resulting high pressure along the axis is distinctly desirable relative to such factors as radiation characteristics and efficiency.

A further important result of the relatively stagnant gas which is present within the arc core 49 is that there is an extremely conductive path between wall 48 and the arcing apex of cathode 26. Such conductive path, the relatively stagnant hot gas within the base portion 68 of the arc, the large area of arcing portion 48 of the anode, and other factors, operate to cause the voltage drop between anode and cathode to be low in comparison to prior-art structures. Thus, for a given power input, the current is relatively high and the voltage relatively low. Because light emission depends largely upon current as distinguished from voltage, the luminous efficiency of the present light source is extremely high.

As previously indicated, the emission of radiation from the arc portions 49 and 68 (FIGURE 4) is substantially different than in various prior-art devices. For example, the microspectral radiancy of the present recessed-plate vortex-stabilized arc shows remarkable axial uniformity in the infrared. Relative to ultraviolet radiation, there is a high emission zone adjacent the cathode 26, the remainder of the arc being substantially uniform relative to light-emission characteristics. There is no hot emission zone in

evidence near the anode, the arc instead increasing in width within the anode recess and contacting the surface 48 over a large area, as stated above.

By changing the diameter of wall 47, and the depth of recess 45, the emission characteristics of the arc may be substantially altered. Furthermore, the physical shape of the arc (including the conical base 68 thereof) may be changed in various desired manners and in accordance with the requirements of the optical system with which the light source is employed. Referring to FIGURE 6, there is shown an anode construction wherein the recess 45a is smaller in diameter and greater in depth than in the anode construction shown in FIGURE 4. The light emitted from the recess, as indicated by the phantom lines 51a, then extends through a smaller angle than in the embodiment of FIGURE 4. However, the cylindrical portion 49a of the arc is smaller in diameter (all other conditions being equal) than in the embodiment of FIGURE 4, and the conical base 68a of the arc is also smaller in diameter.

In the described manner, the aspect ratio of the emitted light, the spectral distribution throughout the arc, the emission intensity of various portions of the arc, and other factors, may be altered or adjusted in numerous desired ways.

As previously indicated, the power capabilities of the present light source are vastly superior than in the case of prior-art light sources of the same general class. For example, the present power source will operate for many hours without substantial deterioration or wear of the electrodes, and at power levels much higher than in the case of the light source described in the above-cited patent application.

The gas employed in the present radiation source should be a noble gas such as (for example) argon, neon, krypton, xenon, or mixtures thereof, at high pressures. The gas pressure within arc chamber 20 should be on the order of hundreds of pounds per square inch.

It has been found that maximum stability of the arc is achieved when the diameter of the cylindrical body of the arc (in chamber 20) is in the range of about one-third to two-thirds of the diameter of the portion of wall 47 nearest the cathode 26. The diameter of such cylindrical portion of the arc should not be as large as that of wall 47, because flow of cold vortex gas into the recess would then be impeded.

It is pointed out that the cathode 26 of the present source is (like the anode) devoid of gas-outlet passages along the axis of the arc chamber. Thus, the stagnant gas condition along the axis is maintained.

The tip of the cathode may be formed of thoriated tungsten, and should be operated at or near the melting point. The bottom wall 48 of the recess 45 may be formed of tungsten, which should also be at a temperature near the melting point.

Specific example

As a specific example of one operative form of the present source, which example is given by way of illustration and not limitation, the diameter of the cylindrical wall of the recess 45 may be 5 mm., and the depth of the recess (between surface 24 and surface 48) may be 2.5 mm. The diameter of each gas conduit portion 52-54 may be 1.5 mm., whereas the diameters of the four gas-inlet conduits 28 may be 0.6 mm. The diameter of the chamber 20 may be 25.0 mm., the spacing between the apex of cathode cone 26 and surface 48 being 11.5 mm.

The arc current may be 150 amperes, and the voltage between the electrodes 85 volts. The gas employed may be argon, at a pressure of 14 atmospheres within arc chamber 20.

The resulting arc had a diameter of 2.0 mm. along the cylindrical portion 49 thereof. The luminous efficiency of the arc was 17 lumens per watt, this being very much better than a typical vortex arc with a straight axial exhaust orifice.

The foregoing detailed description is to be clearly understood as given by way of illustration and example only, the spirit and scope of this invention being limited solely by the appended claims.

I claim:

1. A method of effecting gas vortex stabilization of a high-current electric arc in a chamber, which comprises: maintaining a high-current electric arc between first and second electrodes and along a predetermined axis in an arc chamber, causing at least one footpoint of said arc to extend into a recess in at least one of said electrodes, effecting footing of said arc at the center of said recess, effecting vortical flow of gas about said axis in said chamber, discharging gas from said recess through conduit means located radially-outwardly from said arc, and transmitting light from said arc through a window in the wall of said chamber. 5
2. The invention as claimed in claim 1, in which said method further comprises cooling the walls defining said recess. 20
3. A method of effecting gas vortex stabilization of a high-current electric arc in a chamber, which comprises: maintaining a high-current electric arc in an arc chamber along an axis between spaced electrodes therein, causing one end portion of said arc to extend into a recess having a side wall coaxial with and spaced outwardly from said axis, 25 footing said arc on the bottom wall of said recess, effecting generally tangential introduction of gas into a peripheral region of said arc chamber, preventing discharge of said gas from said recess along said axis, 30 discharging said gas from said recess through passage means which communicate with said recess at at least one region disposed radially-outwardly from said axis, and transmitting light from said arc through a light-transmissive window in the wall of said chamber. 40
4. A method of generating high-intensity light, which comprises: footing one end of an electric arc on the bottom wall of a shallow recess in a metal electrode, 45 footing the other end of said electric arc on a second electrode spaced from said first-mentioned electrode, passing a coolant through said first-mentioned electrode to effect cooling of the side and bottom walls of said recess, causing said arc to extend along an axis which is generally perpendicular to said bottom wall and intersects the same in the central portion thereof, 50 continuously passing high-pressure gas around said arc and thence into said recess, continuously draining said gas from said recess adjacent the side wall thereof, and transmitting to a desired area the light generated by said arc. 55
5. Apparatus for generating high-intensity light, which comprises: 60 wall means to define an arc chamber, at least a portion of said wall means being transparent, wall means to define a foot chamber communicating through an opening with said arc chamber, means to form an arcing surface in said foot chamber in the region opposite said opening and coaxial with said opening, said arcing surface being sufficiently close to said opening, and said opening being sufficiently large 65 in diameter, that light generated in at least the center of said arcing surface may be readily transmitted through said transparent wall means, an electrode having an arcing portion disposed in said arc chamber opposite said opening, 70

- means to effect a high-current electrical discharge between said arcing surface and said arcing portion of said electrode, 5 means to introduce gas into said arc chamber and to effect vortical flow of said gas about an axis which extends from said arcing surface through said opening to said arcing portion of said electrode, and means to drain said gas from said arc chamber through said opening, 10 said drain means including gas-outlet means communicating with said foot chamber at the peripheral region thereof, said foot chamber defined by said second-mentioned wall means being located in an electrode additional to said first-mentioned electrode. 15
6. Apparatus for generating high-intensity light, which comprises: wall means to define an arc chamber, at least a portion of said wall means being transparent, 20 at least a major portion of said wall means comprising a surface of revolution about a central axis, wall means to define a foot chamber communicating through an opening with said arc chamber, 25 said opening being defined by an annular wall coaxial with said central axis, the diameter of said annular wall being much smaller than that of said surface of revolution, means to form an arcing surface in said foot chamber coaxially of said central axis and in the region of said foot chamber opposite said opening, 30 said arcing surface being sufficiently close to said opening, and said annular wall being sufficiently large in diameter, that light generated at at least the portion of said arcing surface at said axis may be readily transmitted through said transparent wall portion, 35 said foot chamber being formed in an electrode incorporating said annular wall and said arcing surface, 40 a second electrode having an arcing portion disposed in said arc chamber opposite said opening, 45 means to maintain a high-current electric arc between said arcing surface of said first-mentioned electrode and said arcing portion of said second electrode, 50 said means being a D.C. source having the positive terminal thereof connected to said first mentioned electrode, and the negative terminal thereof connected to said second electrode, 55 means to introduce gas at high pressure into said arc chamber and to effect vortical flow of said gas in said chamber about said central axis, 60 said gas-introduction means being independent of said foot chamber and of said opening, 65 means to discharge at least a portion of said gas from said arc chamber through said opening, 70 said discharge means including gas-outlet means communicating with said foot chamber, 75 said gas-outlet means including a plurality of passages the intake portions of which communicate with said foot chamber adjacent said annular wall, and means to pass coolant continuously through said first-mentioned electrode to thereby effect cooling of said arcing surface and the walls of said passages. 80
  7. Apparatus for generating high-intensity light, which comprises: light-transmissive wall means to define an arc chamber, 85 first and second electrodes having solid arcing portions disposed in spaced relationship in said chamber, said arcing portions being disposed along a predetermined axis in said chamber, 90

11

one of said arcing portions being in a recess in one of said electrodes,
means to effect vertical flow of gas in said chamber and about said axis,
said last-named means including means to introduce gas continuously into said chamber, 5 means to maintain an electric arc along said axis between said arcing portions, and means to discharge said gas from said chamber through outlet means the intake portion of which is located radially adjacent said one arcing portion and exteriorly of said arc.

8. The invention as claimed in claim 7, in which said last-named means comprises at least three outlet passages having intake ends which are located radially adjacent 15 said one arcing portion and are peripherally spaced there-around.

9. Apparatus for generating high-intensity light, which comprises:

wall means to define an arc chamber, 20 at least a portion of said wall means being transparent, said wall means including a surface of revolution about a central axis, means to define a solid, hole-free arcing surface disposed on the axis of said surface of revolution, 25 means to introduce gas continuously into said chamber and to effect vertical flow of said gas about said axis in said chamber, means to maintain an electric arc along said axis between said arcing surface and an electrode space and 30 insulated therefrom. outlet means located adjacent the region encompassing said arcing surface to continuously discharge said gas from said chamber, and means to define an annular wall in said chamber co- 35 axially with said axis and between said arcing surface and said electrode, said annular wall being sufficiently small in diameter to effect spreading of the portion of said arc extending between said arcing surface and the part of said annular wall nearest said electrode, whereby the diameter of said arc at arcing surface is substantially larger than the diameter of said arc at a region between said annular wall and said electrode, said annular wall being sufficiently large in diameter to permit transmission of light from a point lying on said axis and also on said arcing surface and in a direction having a substantial component radial to said axis, 45 said light passing through said transparent wall means to the exterior of said apparatus.

10. The invention as claimed in claim 9, in which outlet means comprises a plurality of passages the intake portions of which are disposed at least as far from said axis as is the portion of said annular wall which is nearest said axis.

11. Apparatus for generating high-intensity light, which comprises:

light-transmissive wall means including a surface of revolution about a central axis, 60 said wall means defining an arc chamber, a metal electrode having a recess therein, means to pass coolant through said electrode to effect cooling of the side and bottom walls of said recess, means to maintain an electric arc in said chamber between said bottom wall and a second electrode which is spaced and insulated from said metal electrode, said arc extending along said axis of said surface 65 of revolution,

means to continuously introduce high-pressure gas into said chamber and to effect vertical flow of said gas around said axis and thence into said recess, and means to continuously drain said gas from said recess 70

12

through outlet means located adjacent the peripheral portion thereof.

12. The invention as claimed in claim 11, in which said side wall of said recess is annular and is coaxial with said axis.

13. Apparatus for generating high-intensity light, which comprises:

light-transmissive wall means to define a chamber a wall of which is a surface of revolution about a central axis, first and second metal electrodes having end portions disposed in said chamber at spaced points along said central axis, the end portion of said first electrode having a recess formed therein, the side wall of said recess being annular and coaxial of said axis, the bottom wall of said recess being substantially solid and being generally transverse to said axis,

means to effect continuous introduction of high-pressure gas into said chamber,

said means being so directed as to effect flow of gas vertically in said chamber about said axis, means to effect continuous discharge of at least a major portion of said gas from said chamber through outlet-opening means the intake portion of which communicates with said recess adjacent said side wall thereof,

a D.C. current source having the positive terminal thereof connected to said first electrode and the negative terminal thereof connected to said second electrode, said source being adapted to maintain a high-current electric arc along said axis between said second electrode and said bottom wall of said recess, the light generated by said arc being transmitted through said light-transmissive wall means.

14. The invention as claimed in claim 13, in which said current source and said gas-introduction means are so correlated to the diameter of said recess side wall that the portion of said arc in said chamber has a diameter substantially smaller than the diameter of the portion of said recess side wall closest to said second electrode.

15. The invention as claimed in claim 13, in which said end portion of said second electrode is free of substantial gas outlet openings at said axis.

16. A high-intensity radiation source including an anode element effecting a heat-sink and pressure-sink 50 operation, which comprises:

wall means to define an arc chamber, said wall means including a transparent portion to transmit light out of said chamber, anode and cathode elements disposed in said chamber to maintain an arc therein, said anode element comprising a hollow metal body having a recess in the surface thereof, said recess having a bottom wall adapted to provide an arcing surface, said recess having a side wall at least a portion of which is a surface of revolution about a central axis, said hollow body also having a re-entrant portion opposite said recess, said re-entrant portion having water passages therethrough extending from the end of said re-entrant portion to the vicinity of said bottom wall of said recess and thence extending radially-outwardly to the periphery of said re-entrant portion,

a water-separator tube extending into said hollow body and around said re-entrant portion in radially spaced relationship therefrom, means to introduce water to the interior of said water

13

separator whereby to effect flow of water through said water passages in said re-entrant portion and also to effect flow of water through the gap between the periphery of said re-entrant portion and said water separator,
 means to discharge water from the space surrounding said water separator,
 a D.C. power source having the positive terminal thereof connected to said anode and the negative terminal thereof connected to said cathode,
 means to introduce gas into said arc chamber, and
 means to discharge gas from said chamber through said recess and through gas passages formed in said re-entrant portion,
 said gas passages communicating with said recess 15
 adjacent said side wall thereof.

17. The invention as claimed in claim 16, in which

14

5 metal conduit means are provided coaxially of said water separator and in communication with said gas passages leading from said recess, whereby the water entering said water separator flows around said conduit means to effect cooling of discharging gas.
